SHOE TREE

Albert P. Baxendale, Brockton, Mass., assignor to
 United Shoe Machinery Corporation, Flemington, N. J., a corporation of New Jersey

Application May 26, 1942, Serial No. 444,559

4 Claims. (Cl. 12—128.6)

This invention relates to shoe trees, and is herein illustrated as embodied in a two-part tree from which all metal parts have been eliminated, it being an improvement upon the construction shown in Letters Patent of the United States No. 970,165, granted September 13, 1910, upon the application of Charles A. Batchelder.

Two-part shoe trees, such as that described in the Batchelder patent, comprise a forepart and a heel part which are hinged together, by means of a metal pin, to facilitate the insertion of the tree in a shoe. In order that such trees may not only fit the shoes in which they are used more perfectly but may be adapted for different sizes of shoes, the hinge member is commonly provided with a plurality of transverse apertures any one of which is adapted to receive a transverse pin extending through the sides of a bifurcated portion at the rear end of the forepart to vary the size of the shoe tree. Such metal pins, however, are capable of rusting and may therefore stain the shoes. Moreover, when they have rusted, it is difficult to remove the pin and replace it as desired. Accordingly, an object of the invention is to provide an improved shoe tree having a hinge pin of non-metallic construction especially designed to be retained frictionally in the tree.

Inasmuch as a wooden pin must necessarily be cut substantially longitudinally of the grain of the wood, there is danger that shrinkage of such a pin would loosen it to an extent that it might come out of the tree and become lost. The hinge pin herein illustrated, in accordance with a feature of the invention, has an enlarged portion for frictional engagement with the passage in which the pin is received and, as illustrated, the enlarged portion is opposite a groove or notch permitting it to yield as it is positioned in the tree, thereby increasing the friction.

These and other features of the invention will best be understood from a consideration of the following specification taken in connection with the accompanying drawing, in which

Fig. 1 shows a completed all wood shoe tree having two parts hinged together;

Fig. 2 is an angular view of the heel part of such a tree which has been broken away to show a hinge plate; and

Fig. 3 is a side elevation, on an enlarged scale, of a special hinge pin.

The improved shoe tree comprises a forepart portion 10 which is bifurcated at its rear end to provide a slot 12 extending heightwise of the tree, and this bifurcated portion of the tree is pierced by a transverse cylindrical passage 14 adapted to receive a hinge pin 16. The tree also includes a heel part 18, the sides of which merge with the sides of the forepart. This heel part has a handle 20 and is grooved or notched at 22 (Fig. 2) to receive one end of a hinge plate 24 made of plywood and held in position in the

heel part by dowels 26. One of these is received in a transverse aperture while the rearmost dowel passes through an open-ended notch in this hinge plate, thus avoiding the need for undue care in spacing the holes to receive the dowels 26. The forward end of the hinge plate has a plurality of transverse apertures 28 enabling a lengthwise adjustment of the heel piece with respect to the forepart.

- 10 Through the passage 14 and one of these apertures 28 extends the hinge pin 16 about which the heel part pivots. This hinge pin has a notch or groove 30 at one end and the divided portions 32 of the pin adjacent to that notch are spread laterally to form an enlarged portion, the diameter of which is greater than the normal diameter of the passage 14. As illustrated, a wedge piece 34 is preferably glued in position in the notch 30 to hold the portions 32 in their spread condition.
- 15 20 The wedge 34 may be constructed of wood, leather or some other slightly yieldable material. By reason of these spread end portions 32 the pin will be held frictionally in place regardless of any shrinkage of the parts and yet may be readily removed for replacement in any of the holes 28 of the hinge plate.

Having thus described my invention, what I claim as new and desire to secure by Letters Patent of the United States is:

- 30 1. In a two-part last-like member, a hinge pin having a grooved portion provided with an insert, shorter than the grooved portion, resiliently holding said portion outside the normal contour of the pin.
- 35 2. A hinge pin, for a two-part last-like member having a cylindrical hole in one of its parts, said hinge pin being adapted to be inserted in said hole and having a notched end portion the outer sides of which are flared for frictional engagement with said hole and yield upon engagement with the sides of the hole.
- 40 3. In a shoe tree, a forepart member for the forepart of a shoe, and a heel member, one of said members being provided with a bifurcated end portion, the other having a projecting hinge plate received in said bifurcated portion, said hinge plate having a plurality of apertures to enable the length of the tree to be adjusted, and a removable hinge pin extending through the bifurcated portion and one of the holes of the hinge plate, said hinge pin being provided with a notched portion and means for urging the sides of the pin at the notched portion to spread laterally beyond the normal diameter of the pin.
- 45 50 55 4. In a wooden shoe tree made up of two portions which are hinged together, a wooden hinge pin provided with a groove at one end parallel to the axis of the pin and a wedge-shaped member inserted in said groove to spread the end portions adjacent thereto.

ALBERT P. BAXENDALE.
